(57) **CLAIM**

The ornamental design for a headset article for electronic device, as shown and described.

DESCRIPTION

FIG. 1 is a perspective view of a headset article for electronic device showing my new design according to a first embodiment;

FIG. 2 is another perspective view of the headset article;

FIG. 3 is a front elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a perspective view of a headset article for electronic device showing my new design according to a second embodiment;

FIG. 8 is another perspective view of a headset article according to the second embodiment;

FIG. 9 is a front elevational view of FIG. 7;

FIG. 10 is a left side elevational view of FIG. 7;

FIG. 11 is a right side elevational view of FIG. 7; and,

FIG. 12 is a top plan view of FIG. 7.

The broken line showing of environment is for illustrative purposes only and forms no part of the claimed design.
